UNITED STATES PATENT OFFICE.

PAUL E. KLOPSTEG, OF CHICAGO, ILLINOIS, ASSIGNOR TO CENTRAL SCIENTIFIC COMPANY, OF CHICAGO, ILLINOIS, A CORPORATION OF ILLINOIS.

ADVERTISING DEVICE.

Application filed June 25, 1925. Serial No. 39,481.

This invention relates to advertising and has for its object to produce movement of some article such as a coin, doll, or the like, within a limited area by invisible forces produced by concealed means. Generally speaking, this is accomplished by making the object include some conducting material and supporting it on a poor conductor within a rotatory magnetic field.

10 A simple and preferred form of means for accomplishing this object is illustrated in the accompanying drawings wherein

15 Fig. 1 is a wiring diagram showing how single phase alternating current may be applied to a Gramme ring to produce a rotatory magnetic field;

20 Fig. 2 is a sectional view illustrating a Gramme ring and a large watch glass in suitable relation for accomplishing the desired object;

Fig. 3 is a side elevation showing the watch glass and Gramme ring associated with a casing for concealing the ring, and

25 Fig. 4 is a side elevation of a casing for enclosing a portion of the electric devices used in connection with the Gramme ring.

30 Referring to the diagram in Fig. 1, 10 indicates the laminated core of the Gramme ring equipped with a winding 11. Single phase alternating current is supplied to the ring by a conductor 12 connected with the winding 11 at 13 by a lead 14, at 15 by a choke coil 16 and a lead 17, and at 18 by the choke coil 16, a non-inductive resistance 19

35 and a lead 20.

This apparatus produces a rotatory magnetic field particularly suited for the objects of this invention because it varies in intensity, form and location with respect to the ring. The choke coil and non-inductive resistance may be mounted within a box 21 to permit them to be readily located in a position entirely concealed from view. The Gramme ring is preferably concealed within a casing 22 of opaque material provided with a seat at its top for a large watch glass 24 on which the article to be moved is supported. A cylindrical skirt 27 extends through the casing and conceals the inner portion of the ring from view. If desired, a lamp 26 may be located beneath the watch glass to illuminate it and the rotating object although the ordinary window illumination will, in most cases, be sufficient for that purpose.

A device so constructed may be readily located in a show window or any other place where it is desired to attract attention. It is set in operation by closing the circuit, supplying the current to the Gramme ring and setting the coin or other object spinning in the proper direction on the watch glass. The rotatory magnetic field will induce eddy currents in the metal of the coin, or small piece of conducting material, in a doll or the like, and cause it to spin about its base. With such a varying magnetic field the coin or other object will not only spin, but will travel an uncertain path about the watch glass.

It is necessary that the support be of poorly conducting material and the watch glass is preferred because it has this quality, is transparent and is a stock article. By illuminating the watch glass the mystery as to the force causing the movement is increased because it permits the observer to see that there are no moving parts beneath the support and within the circumference of the ring. The concavity of the watch glass serves to restrain the spinning article from working off the edge of the support, and also adds mystery to the cause of the wandering movement. It is, however, not essential to the broad aspects of the invention that the support be of transparent material or have a concave upper surface, although it is necessary that the support be of poorly conducting material. A smooth surface on the support contributes to the spinning movement, but it is not necessary that the surface have any regular form, and bumps, ridges or other irregularities, may be used to heighten the mysterious effect or control the path of travel.

A rotatory magnet field may be produced by combining alternating currents by a great variety of means, some of which may be arranged to produce a field of substantially uniform characteristics as, for example, by applying either three phase alternating current in star or delta connection or two phase alternating current in quadrature.

This invention lends itself to a great variety of forms also in the nature of the object. For use in banks a coin is appropriately suggestive and adds to the mystery by reason of its remaining on edge as well as its spinning and wandering movement. For

other places other objects will have particular advantages. For example, in the juvenile department, a cat or dog chasing its tail might attract more attention than a coin 5 spinning.

Use has been made of specific description and illustration in order to disclose the invention, but it is intended that nothing contained herein shall unnecessarily limit the 10 following claims, or require a construction thereof that would permit the substance of the invention to be used without infringement.

I claim as my invention:

15 1. In an advertising device, the combination of a support composed of poorly conducting transparent material presenting a smooth surface on top, means for illuminating the support, stationary means adjacent 20 to the support for producing a rotatory magnetic field over said smooth surface, and an object including conducting material and resting on said surface with a relatively small area of contact compared with the 25 total area of the object.

2. In an advertising device, a support of poorly conducting material presenting a smooth surface at its upper side, an object including conducting material resting on 30 and presenting a relatively smooth area of contact to the smooth surface of the support, and stationary means adjacent to the support for producing an unsymmetrical rotatory magnetic field extending over the surface of the support.

3. In an advertising device, the combination of a casing having an opening on its upper side, a transparent support extending across said opening, means within the 40 casing to produce a rotatory magnetic field above the support, a tubular shield extending downwardly from said opening to conceal said means from view through said support, means to illuminate the space in the casing below the support, and an object 45

containing conducting material freely rotatable on the support.

4. In an advertising device, the combination of a coil lying generally horizontal, a source of alternating current and connections between the source and the coil for producing a rotary magnetic field, means for concealing the coil from view, a suggestive object including a conductor, and means to support the object for spinning movement in the field about an upright axis. 55

5. In an advertising device, the combination of a support of poorly conducting material, a Gramme ring adjacent to the support, means for connecting the Gramme ring 60 with the source of alternating current and an object resting on the support with a relatively small area of contact and including conducting material.

6. In an advertising device, the combination of a Gramme ring, a watch glass above the ring, means for connecting the ring with the source of alternating current to produce a rotatory magnetic field, and a conductor adapted to spin on said glass. 65

7. In an advertising device, the combination of a casing having a vertical opening therein, means surrounding said opening for producing a rotatory magnetic field, a support of poorly conducting material above 75 said opening and a rotary object resting on said support and including conducting material.

8. In an advertising device, the combination of a support presenting a smooth surface on top, an object including conducting material resting on and presenting a relatively smooth area of contact to the surface of the support, and means adjacent to the support for combining alternating current 80 to produce a rotatory magnetic field including said object. 85

In testimony whereof I affix my signature.

PAUL E. KLOPSTEG.
